UNITED STATES PATENT OFFICE.

LOUISE A. STERRY, OF LOS ANGELES, CALIFORNIA.

WEARING APPAREL.

Application filed May 4, 1921. Serial No. 466,640.

This invention relates to wearing apparel, and more particularly to a device to be used or worn by the operator or driver of a vehicle, particularly a motor car, which use tends to properly confine the clothing as well as protect it. The device is adapted to be applied over skirts, and trousers or other bifurcated nether limb garments, and to extend around the limbs and upwardly and around a portion of the body of the user. Suitable means are provided for holding the garment or article in position of service, and whereby the garments may be quickly and conveniently applied to the user and likewise detached after use.

A device of this character serves all the functions and offices of a lap robe, including both warmth and protection, and at the same time leaves the nether limbs free to be used in operating change gear and brake and other automobile pedals. It likewise protects the garments from dust, dirt, grease and other substances to be encountered in vehicle operation, forming a serviceable lap robe or apron usable in case of vehicle repair or adjustment, and confines the nether limb garment, such as trousers, so that the same is prevented from becoming entangled with any of the devices and apparatus for operating and controlling the vehicle.

The invention has for a further object the provision of an improved device or article of manufacture of the character above generally stated which will be superior in point of relative simplicity and inexpensiveness of formation and construction, taken in conjunction with compactness in form when out of use and folded, durability, neatness in appearance, and general efficiency and serviceability.

With the above and other objects in view the invention consists in the novel and useful formation, construction, combination and relative arrangement of parts, members and features, all as hereinafter described, shown in the drawing, and finally pointed out in claims.

In the drawing:

Figure 1 is a perspective view showing the figure of a motor car operator in position to operate the car, certain of the controlling members of the car being indicated by dotted lines, and a device embodying the present invention being shown as applied to the operator; and,

Figure 2 is a fragmentary plan view of the device or garment shown in Figure 1, the same being in detached position and extended out in flat form.

Corresponding parts in both figures are designated by the same reference characters.

Referring with particularity to the drawing, the invention comprises in the main a flexible extended body portion A, which may be of textile material, rubberized or otherwise treated to resist moisture, or may be of leather or other suitable and durable material. This central body portion is provided at upper and lateral extremities with flaps or extensions B and C, and at lower and lateral extremities with flaps or straps D and E. One of the upper flaps, as B, is provided with a series or plurality of fastening devices b, such as buttons, adapted to co-act with a button hole or the like c, formed in the flap C. Upon the body member A, and suitably positioned to co-act with the flaps D and E, respectively, are provided fastening devices such as snap fastener members a with which co-act snap fastener members d and e, which are respectively provided upon the flaps D and E.

In applying the article or device to the user or wearer, the central body portion A is placed across the front of the wearer, extending upwardly of the body to a suitable height and extending downwardly substantially to the feet of the wearer. The flaps B and C are then brought together in overlapping relation rearwardly of the user and so held by the fastener devices b and c. The flaps D and E are then extended respectively around the nether limbs, first forwardly of the limbs and then backward of the limbs and up between the limbs into such positions that the fastening devices d and e may respectively co-engage with the fastening devices a. The lower edge portion of the body member A is preferably notched or cut away, as at f, in the median zone, thus accommodating the straps D and E in their extension upwardly between the limbs as above recited.

A pocket g may be provided on the central body A, at the forward or outer face of the same, and it will be understood that the fastening devices b and a are on the outer or forward face of the device, the fastening members d and e being on the inner face of the device.

With the garment or article applied in the manner described, the limbs of the wearer are surrounded and protected adjacent to the feet, and above the feet and upwardly to a certain zone of the body the wearer is substantially surrounded and encased by and in the article. The purposes of a lap robe are thus accomplished, namely, the conserving of the warmth of the body of a user and protection from cold winds, dampness or other effects of the elements. The reasonably free and unhampered use of the lower limbs is permitted, and there are no loose portions left free to become displaced and uncover the user, or obstruct or interfere with the operation of the vehicle. Likewise, the nether garment is closely confined and prevented from catching in any working part of the vehicle or its controlling members. The device likewise protects the clothing of the wearer, where it covers the same, from dirt, grease and other objectionable or harmful substances.

The side edges of the device come approximately into meeting relation behind and beneath the wearer, who, in his position upon the seat, rests his weight upon such edge portions, which assists in maintaining the article or garment in its proper position of service.

The device may be very readily and rapidly applied and secured in place and likewise removed, and may be stowed away in a tool box or in a door flap or other convenient receptacle. The device may also be worn when repairing or tinkering with the vehicle, as a protection against tearing or soiling of the clothing, and when so used will have many of the advantages which enter into its normal or customary use.

It is obvious that many changes and variations may be made in practicing the invention, and in departure from the specific details and features of construction and formation above set forth, all without departing from the true spirit of the invention.

Having thus disclosed my invention, I claim and desire to secure by Letters Patent:

1. A garment including a body portion formed with upper and lateral extremities and lower and lateral extremities, said body portion being shaped to cover the front and sides of the wearer's body and legs, a pair of flaps extending from the upper and lateral

extremities of said body portion to be extended around the back of the wearer, detachable fastening means for fastening said flaps together in the back of the wearer, a pair of straps extending from the lower and lateral extremities of said body portion, to be extended around the lower portion of the wearer's legs and upwards along the sides thereof, and means for detachably securing said straps to said body portions when said straps are so extended.

2. A garment including a body portion formed of a single unsevered sheet of material and shaped to cover the front and sides of the wearer's body and legs, said body portion likewise being provided with upper and lateral extremities and lower and lateral extremities, a pair of flaps extending from the upper and lateral extremities of said body portion, to be extended around the back of the wearer, detachable fastening means for fastening said flaps together in the back of the wearer, a pair of straps extending from the lower and lateral extremities of said body portion, to be extended around the lower portion of the wearer's legs and upwardly along the sides thereof, and means for detachably securing said straps to said body portions when said straps are so extended.

3. A garment including a body portion formed of a single unsevered sheet of material and shaped to cover the front and sides of the wearer's body and legs, said body portion likewise being provided with upper and lateral extremities and lower and lateral extremities, a pair of flaps extending from the upper and lateral extremities of said body portion, to be extended around the back of the wearer, a pair of straps extending from the lower and lateral extremities of said body portion, to be extended around the lower portion of the wearer's legs and upwardly along the sides thereof, and means for detachably securing said straps to said body portions when said straps are so extended.

In testimony whereof, I have signed my name to this specification.

LOUISE A. STERRY.
